Attorney

UNITED STATES PATENT OFFICE.

FRED W. SIMMONS, OF GRAND ISLAND, NEBRASKA.

WIRE TIGHTENER AND STRETCHER.

Application filed March 10, 1927. Serial No. 174,327.

This invention relates to devices for tightening and stretching wires and particularly stretching wire fences.

The general object of the invention is to provide a very simple and effective device of this character which may be cheaply made, readily used, and which is particularly adapted to stretching adjacent panels of wire fencing between rather widely separated posts so as to permit the longitudinal wires of these panels to be operatively engaged with each other while the fabric of the fence is taut.

A further object is to provide a device of this character having levers so formed that the levers may be used in bending the wires where the wires pass through the loops on one section of a panel.

My invention is illustrated in the accompanying drawings wherein:—

Figure 1 is a side elevation of a fence tightener constructed in accordance with my invention in use;

Fig. 2 is an elevation of the tightener partly broken away;

Fig. 3 is a top plan view of the tightener in use;

Fig. 4 is a rear elevation of the tightener with the wires threaded therethrough;

Fig. 5 is a like view to Figure 4 but showing the wires threaded and tautened by rotation of the tightener.

Fig. 6 is a top plan view of lever and hook, embracing the pipe.

Referring to these drawings it will be seen that my wire tightening device comprises a pipe 10 which may have any desired length but preferably a length equal to or somewhat greater than the height of the fence to be put up. This pipe is formed with a plurality of diametrical openings 11 through which the longitudinal strands of a wire fence may be placed and it is also formed with a plurality of openings 12 extending diametrically through the pipe and having a larger diameter than the openings 11 and a plurality of openings 13 of the same size as the openings 12 extend through the pipe at right angles to the openings 12.

Coacting with these openings are rods or levers 14 having a diameter such as to fit within the openings 12 and 13 and constitute means whereby the pipe may be rotated. One or more of these levers is preferably

formed with a semi-circular portion 15 at 55 one end having a bill 15^a at its extremity, the bill formed on the end of the semi-circular portion 15 being disposed at an angle to the plane of said semi-circular portion.

In one use of this device, the pipe is placed 60 parallel to and against a post to which the wire fence is to be attached. It may be held in this position either by friction or by wire eyes or other suitable means. The wires of the fence are placed through the 65 openings 11 and then the pipe 10 is rotated by means of the levers until the wire is stretched to the degree necessary, after which the wires may be fastened to the post.

While this is one manner of using this 70 wire stretcher, it is particularly applicable for use where two panels of fence are to be joined between posts. Wherever much corn is raised, it has been the custom to "hog down" some of the corn and a woven wire is 75 stretched around that part of the field so used and very few posts are planted as the fence will have to be taken down in a month or so. It is desirable to stretch the fence fabric very tight and practice has shown 80 that it is best to stretch the wire at the splices between the ends of the length of wire fencing as there is less danger of pulling up the end post which may perhaps be as much as twenty rods away. Furthermore, 85 there is more room to work at a distance from the post as the end post is usually a corner post and has several braces which would interfere with the proper manipulation of the stretching device. Under these 90 circumstances loops 16 are formed in the ends of the longitudinal wires 17 of one panel and the longitudinal wires 17^a of the other panel are inserted through these loops and through the apertures 11 in the pipe 10. 95 The pipe is then turned in a counter-clockwise direction and to any degree required which will tighten up these wires 17^a.

After the longitudinal wires have been 100 stretched to the degree required, one wire is unwound from the stretcher, passed through the loop 16 and spliced and by unwinding one wire at a time and crimping it or splicing it, all of the longitudinal wires may be kept taut until the complete splice is made. The hook 15^a is used as illustrated in Figure 6 to 105 bend the wires into a hook which prevents any slackening of the tension if the stretcher

be unwound and after the wires have been so bent the stretcher may be rolled back and all of the wires released and tied or spliced. The lever 14 with the crook 15 and the bill 15^a on the end of the crook 15, which bill extends at right angles to the plane of the crook, is a very important feature of my invention, as by this means it is possible to take up the slack of the wire not necessarily at the corner end post, as by its means this tensioning device and wire splicer may be used at the place where the splice is or where the wire is broken. The tension in a wire fence is lost in the course of time and the fence wires must be re-stretched in a year or two. A stretcher which can take up the slack at the point where the splice is instead of at the anchor post is particularly valuable, inasmuch as at the anchor post the braces are in the way, and furthermore the wire is so securely fastened that it takes more time to loosen it. The manner of using this stretcher for the purpose of stretching the wire at the splice is shown in Figures 5 and 6 and in these figures, as shown, the lever 14 with the crook 15 is disposed in such position around pipe 10 that the hook may be engaged with the wire 17^a and the slack taken out of the wire and the slack held while the

free end of the wire is returned upon itself 30 and fastened to form an eye, as shown in Figure 5.

My device is extremely simple but I have found it very effective for the purpose intended and that by its means I can secure 35 thoroughly good tension upon the fence wires.

I claim:—

A wire tightener of the character described comprising a length of pipe formed with a 40 plurality of diametrically extending passages through which strands of wire may be passed, means for rotating the pipe, and a lever formed at an extremity with an approximately semi-circular portion adapted 45 to be disposed to partially embrace and fit on the pipe, the extremity of the semi-circular portion being formed with a bill extending at an angle to the plane of the semi-circular portion whereby the semi-circular 50 portion may be disposed around the pipe and the bill engaged with a wire passing through the pipe to thereby take up slack in the wire and hold the slack while the free end of the wire is formed into an eye. 55

In testimony whereof I hereunto affix my signature.

FRED W. SIMMONS.
